APPARATUS FOR PHOTOGRAPHIC REPRODUCTION

Harry H. Sullivan, Rochester, N. Y., assignor to
 Paragon Revolute Corporation, Rochester,
 N. Y., a corporation of New York

Application June 1, 1934, Serial No. 728,528

6 Claims. (Cl. 95—75)

This invention relates to a method of photographic reproduction and to a photographic printing machine for performing the same.

At the present time when it is desired to ink a pencil drawing or when a tracing becomes worn or there is need for duplicate tracings, the practice is for a draftsman to draw in the inked lines. This method is not only slow and expensive but entails checking to insure that there have been no mistakes made in copying. In accordance with the present invention, it is proposed to photographically reproduce such pencil drawings, tracings and the like on tracing cloth or other like material having a coating thereon which is highly sensitized to light.

The main feature of the invention relates to a novel photograph printing method by which a wide variety of originals including tracings, blue-prints, half-tones and the like, even of large size, may be quickly and conveniently reproduced photographically with uniformly satisfactory results.

Another feature of the invention relates to a photographic printing machine for performing the several steps of the novel printing method.

Still another feature of the invention relates to the design of a photographic printing machine which may be easily adjusted to reproduce originals such as tracings and the like of varying character and contrast.

These and other features of the invention will appear from the detailed description and claims when taken with the drawings in which Fig. 1 is a front elevation of a photographic printing machine according to the present invention; Fig. 2 is an end elevation of the left end of the machine as shown in Fig. 1; Fig. 3 is a vertical section thereof taken substantially on the line 3—3 of Fig. 1, a portion of the section being broken away; Figs. 4 and 5 are also vertical sections taken substantially on the lines 4—4 and 5—5 looking in the direction of the arrows; Fig. 6 is a detail view of a fragment of a brush which is used in stripping the original sheet and the exposed photographic sheet from the cylinder; Fig. 7 is a sectional view taken substantially on the line 7—7 of Fig. 3 illustrating a portion of the driving arrangement for the cylinder; and Fig. 8 is a vertical sectional view taken substantially on the line 8—8 of Fig. 3 indicating the manner in which the speed of rotation of the cylinder is changed.

The photographic printing or reproducing machine of the present invention is primarily intended for use in a dark room. Referring espe-

cially to Fig. 1, there is illustrated a preferred form of the machine having a frame including the uprights 5 and 6, cross bars 7, 8, and 9 and suitable diagonal braces 10 and 11. Near the top of the frame, and at a convenient height for the operator, there is provided a work table T and a rectangular hood 12 formed of sheet metal having a work receiving opening adjacent the table, the ends of the hood being respectively connected by light-tight joints to the upper portions of the uprights 5 and 6. As shown in Fig. 3, the hood is formed of a top section 13, a rear section 14 and a bottom section 15, the front of the hood being open except for the top strip 16 and the bottom strip 17 which define the work receiving opening. There is provided within the hood 12 and extending lengthwise thereof, spaced rotatable parallel rolls 23, 24, 25, and 26 which are suitably mounted at their ends. A plurality of continuous belts 27 pass around these rolls 20 and also partially encircle a hollow transparent cylinder 28 preferably formed of transparent glass. As herein disclosed, the rolls 23, 24 and 26 are journaled at their ends in the uprights 5 and 6, while the roll 25 is mounted at its respective ends on bell crank levers 29 pivoted at 30 on the respective uprights 5 and 6. The arms 31 of these levers are held under tension by coil springs 32, each having one end fastened to a stationary part of the frame so that the roll 25 maintains the belts 27 taut at all times.

A rectangular lamp housing 23 having its respective ends secured in light-tight engagement with the upper portions of the uprights 5 and 6 extends through the transparent cylinder 28. On the front wall of the lamp housing, there is detachably supported in brackets 33, a mercury arc lamp L which is slightly shorter than the housing 33. These brackets hold the lamp with its long axis inclined to the horizontal, and also serve as terminals for connecting its electrodes to a source (not shown) of electric lighting current. The rear wall of the lamp housing is provided with an exposure aperture of a length substantially equal to that of the mercury lamp which aperture is inclined with respect to the horizontal as best indicated in Fig. 5 in order to be in substantial alignment with this lamp. This aperture is bounded at its lower edge by an angle bar 34 attached to the housing and having one flange thereof projecting approximately to the inner surface of the transparent cylinder. At the upper edge of this aperture, there is mounted for limited vertical adjustment

an angle bar 35, which also has one of its flanges extending approximately to the inner surface of the transparent cylinder and which has its other flange attached to the housing by guide 5 screws 36 passing through vertical slots in this flange and threaded into the rear wall of the housing. It will be understood that the angle bar 35 is vertically adjustable by means of links 37 which pass through slotted guides 38 in the 10 ends of the housing, the upper end of each link 37 being pivotally connected to an arm 39 in turn eccentrically pivoted at 40 on a knurled hand disk 41. One of these disks is mounted on each end of a horizontal shaft 42 which is rotatably mounted in the uprights 5 and 6 at each 15 end of the hood. In the face of each disk adjacent its related upright, there are provided a series of notches 41a to receive a ball 43 supported by a spring 44 on the respective uprights. 20 The engagement of these balls with the mentioned notches, tends to retain the disks in the position to which they have been manually adjusted.

The upper portion of the uprights 5 and 6 have 25 openings therein leading to the interior of the lamp housing, these openings being closed by the covers 18 and 19. The cover 19 also serves as a shield for a nozzle 20 which communicates through a pipe 21 with a suitable blower 22a, 30 driven in any well-known manner such as by an electrical motor (not shown), to supply a stream of cooling air to the interior of the housing. The cover 18 as indicated in the upper left hand corner of Fig. 1 has a light-trapped outlet 22 through 35 which the stream of air flowing through the hood from the nozzle 20 and blower 22a escapes. It will be understood that this stream of air is necessary in order to maintain the mercury arc lamp at suitable operating temperatures.

40 Under certain conditions of operation of the machine, it is desirable to vary the character of light passing through the aperture in the lamp housing. For this purpose there is provided a light filter F substantial coextensive with the 45 aperture and formed of a strip of color screen reinforced by a metal border. This filter is pivotally mounted at its ends on the uprights 5 and 6 at points 45, for movement to the position shown, so that no light from the lamp 23 can 50 pass through the aperture except through the filter. In order to swing this filter away from the aperture, there is pivotally connected to the lower edge of its metal border, links 47. Each of these links is pivoted at 48 to one arm of a 55 bell crank lever 50 secured to the shaft 49. The other arm 50a of each bell crank lever serves as a handle by which these levers can be moved from the position shown in Fig. 3 as limited by the engagement of stop 51 with an extension of 60 the upright, to the position where this stop engages the lug 52 on the mentioned extension.

It has been mentioned that the cylinder 28 is 65 driven by a plurality of belts passing around the rolls 23, 24, 25, and 26, the power for driving these belts being applied through roll 26 from the motor 54. A pulley 55 on the shaft of this motor drives a belt 56 engaging the periphery of the pulley 51. This pulley is secured to a shaft 58 suitably journaled on the upright 5 and normally urged to 70 the right (as shown in Fig. 3) by a coil spring 59 having one end engaging a portion of the upright and its other end engaging a sleeve 60 secured to the shaft 58. The right hand face of pulley 51, as shown in the mentioned figure, en- 75 gages the periphery of a friction roller 61 secured

to the rotatable, vertical shaft 62, which roller and its shaft are adjustable vertically as will be described. The roller 61 at its periphery also engages the face of a disk 63 which is spaced from the disk 57 and which is secured to the horizontal 5 shaft 64. This shaft is mounted in suitable bearings in the frame and is provided at its free end with a worm 65. The worm 65 cooperates with a worm gear 66 attached to a shaft 67 in common with the sprocket 68 which shaft is suitably journaled in the frame. This sprocket drives a chain 69 serving to drive the sprocket 70 mounted on the shaft 71. Shaft 71 which is supported on the upright 5, is provided with a gear 72 meshing with a second gear 73 mounted on the 10 shaft 74 of the roll 26. The chain 69 is maintained taut by an idler sprocket 75 mounted on an arm 76 in turn pivoted at 77, the arm 76 having a set screw 78 to engage a lug 79 on the frame so that the tension of the chain can be 15 adjusted at will. In order to adjust the speed of the cylinder without disturbing the speed of the motor, the roller 61 is employed as a part of a frictional speed control unit. This roller 20 as best shown in Fig. 8 has its shaft 62 journaled in a bifurcated support 80 which is slidably mounted on the rod 82. The support has connected thereto at 83, a link 84 which is pivoted at 85 on one end of an arm 86 adapted to rock about the pivot 87 as an axis. The other end 30 of the arm 86 has connected thereto at 88, a link 89 pivotally connected at 90 to an arm 91 projecting from a sector rack 92, which is pivoted at 93 on the frame. The rack meshes with a pinion 94 mounted on the shaft 95 of a hand wheel 96, the shaft being suitably journaled in the frame. A set screw 97 having a knurled hand grip, locks the hand wheel in the position to which it has been adjusted. If desired, the exposed surface of the hand wheel 96 may be graduated in units of exposure time, which graduations are successively brought into registry with the stationary index 101 as the hand wheel is 40 rotated.

During the operation of the machine, the mercury arc lamp L is lighted in the well-known manner to furnish a light source substantially co-extensive in length with the exposure aperture in the lamp housing as shown in Fig. 3. This exposure aperture as herein illustrated, is covered by the color screen or filter F to vary the character of light transmitted to the exposure aperture. At this time the motor 54 is started to drive the belts 27 and the glass cylinder 28 in the direction indicated by the arrows. This drive is effected through the pulley 55 on the shaft of the motor, belt 56 engaging the periphery of the pulley 51. The power is thence transmitted through the frictional speed adjusting unit including the face of the pulley 51, roller 61, disk 63, shaft 64, worm 65 and worm gear 66. These parts rotate the sprocket 68 to drive chain 69, which in turn drives the sprocket 70 and this sprocket drives the gear 72 meshing with the gear 73 mounted on the shaft 74 of the roller 26. The roller 26 drives the belts 27 which in turn rotate the glass cylinder 28.

With the lamp lighted and the cylinder rotating, a suitable original such as a tracing or the like is placed on the table T in superimposed relation to a sheet of sensitized material. The superimposed sheets are then pushed along the table into the front of the hood until they are gripped between the glass cylinder 28 and the belts 27, and are advanced thereby. As the orig- 75

inal sheet and the sensitized sheet pass by the exposure aperture, the image on the original is progressively photographed on successive portions of the sensitized sheet until all of the image on the original is photographed on the sensitized sheet. The glass cylinder 28 and the belts 21 then continue to advance the superimposed sheets until they are deposited in the work receiving tray 30. A narrow brush 100 coextensive in length with the cylinder 28 and mounted on the lower edge of the tray, is provided to separate the sheets from the cylinder and to guide them to the work receiving tray 30.

In the event that it is desired to vary the width of the aperture in the lamp housing, for example, if it is desired to increase the width of this aperture, one of the hand disks 41 is rotated clockwise as shown in Fig. 3. The arms 39 which are eccentrically attached to these disks, are thereby elevated and the links 37, connected to them, are raised so that the angle bar 35 is elevated with the resultant increase in the width of the aperture. A counter-clockwise movement of the mentioned disks results in the operation of the arms 39 and links 37 in the reverse direction to force the angle bar 35 toward the angle iron 34 with the consequent decrease in the width of this aperture. It will be understood that the notches in the disks 41 receive the spring pressed balls 43 to hold these disks in the positions to which they have been moved so that the aperture will be maintained at its adjusted width.

In the event that the character of the original is such that the full effect of the light from the lamp 23 is necessary to photograph the original on the sensitized sheet, the color screen or filter F is swung away from the aperture in the lamp housing. This is effected by swinging either of the handles 56a in a clockwise direction (see Fig. 3) until the stop 51 engages the lug 52. By this swinging movement of the handle, the links 47 are elevated and since they are pivotally connected to the lower edge of the filter, the filter is swung to a substantially horizontal position 45 out of the path of light to the aperture.

With originals of different character, it is desirable to have different speeds of exposure, and this result is obtained by varying the speed at which the original sheet and the sensitized sheet 50 are fed past the aperture in the lamp housing. This change in speed is effected by loosening the set screw 97 and then rotating the hand wheel 96. If it is desired to increase the speed of exposure, the hand wheel is rotated counterclockwise (see Fig. 3). Hand wheel 96 rotates the pinion 84 in a counterclockwise direction to drive the segment 92 in a clockwise direction so that its arm 91 lowers the link 89. Link 89 then rocks the lever 86 and through the link 84 (Fig. 9) elevates the bifurcated support 88 in which the roller 61 is rotatably mounted. This roller is thereby elevated and serves to increase the speed at which the disk 63 is driven from the pulley 57. The disk 63 through the remaining elements 65 previously described serves to rotate the belts 21 and the cylinder 28 at a faster speed than prevailed prior to the adjustment. When the desired adjustment has been made the set screw 97 is turned to its locking position and the hand wheel 70 96 is thus locked in its adjusted position. In the event that it is desired to reduce the speed of exposure, the set screw 97 is loosened and the hand wheel is rotated in a clockwise direction with the result that the roller 61 is lowered so 75 that it drives disk 63 more slowly.

What I claim is:

1. In a device of the class described, a hollow rotatable transparent work support, means for holding an original and a light sensitized sheet on the surface of said support, a dark compartment containing said work support, a lamp housing mounted within said support, said housing being light-tight, except for a narrow elongated exposure aperture therein, said aperture being inclined to the horizontal, and a uniform source of light within said housing, said source being substantially co-extensive with said aperture and having its principal axis generally parallel to the principal axis of said aperture.

2. In a device of the class described, a dark compartment, a hollow transparent cylinder rotatable in said compartment, means for rotating said cylinder, a lamp housing having a narrow elongated exposure aperture therein adjacent said cylinder, said aperture being inclined to the horizontal, and a light source within said housing, said source being substantially co-extensive with said aperture and having its principal axis generally parallel to the principal axis of said aperture and also having a substantially uniform light intensity throughout its length.

3. In a device of the class described, a dark compartment, a hollow transparent cylinder rotatable within said compartment, at least one belt engaging a substantial portion of the outer surface of the cylinder for rotating the same and for holding an original sheet and a sensitized sheet in superimposed relation against the outer surface of said cylinder, a lamp housing within said cylinder, said housing being light-tight except for a narrow elongated exposure aperture therein inclined to the horizontal and located adjacent the inner surface of said cylinder, a source of light within said housing of a length substantially equal to the length of said aperture and of substantially uniform intensity throughout its length, an adjustable shutter for varying the width of said aperture and means for continuously driving said belt at a speed adjustable at will.

4. In a device of the class described, a dark compartment, a hollow transparent cylinder rotatably mounted within said compartment, at least one belt engaging a substantial portion of the outer surface of the cylinder for rotating the same and for holding an original sheet and a sensitized sheet in superimposed relation in contact with the outer surface of the cylinder, a lamp housing within said cylinder, said housing being light-tight except for a narrow inclined exposure aperture therein, adjacent the inner surface of said cylinder and of a length approximately equal to the length of the cylinder, an adjustable shutter for varying the width of said aperture, a source of light within said housing parallel to said aperture, of a length substantially equal to the length of said aperture and of substantially uniform light intensity throughout its length, a uniform speed motor, and an adjustable speed transmission through which said motor drives said belt continuously whereby the speed of rotation of said cylinder can be adjusted at will.

5. In a device of the class described, a dark compartment, a hollow transparent cylinder rotatably mounted within said compartment, at least one belt engaging a substantial portion of the outer surface of the cylinder for rotating the same and for holding an original sheet and a

sensitized sheet in superimposed relation in contact with the outer surface of the cylinder, a lamp housing within said cylinder, said housing being light-tight except for a narrow inclined exposure aperture therein, adjacent the inner surface of said cylinder and of a length approximately equal to the length of the cylinder, an adjustable shutter for varying the width of said aperture, a source of light within said housing parallel to said aperture, of a length substantially equal to the length of said aperture and of substantially uniform light intensity throughout its length, light-reducing means movable at will into and out of the path of light passing through said aperture, a uniform speed motor, and an adjustable speed transmission through which said motor drives said belt continuously whereby the speed of rotation of said cylinder can be adjusted at will.

10 15 20 6. In a device of the class described, a dark

compartment, a hollow transparent cylinder rotatable in said compartment, at least one driven belt engaging the outer surface of the cylinder for rotating the same and for holding an original sheet and a sensitized sheet against the outer surface of the cylinder, a lamp housing within the cylinder, said housing being light-tight except for an exposure aperture therein adjacent the inner surface of said cylinder, said aperture being inclined to the horizontal, a source of light of a length substantially equal to the length of said aperture and having its principal axis parallel to the principal axis of said aperture, one end of said housing having a light trapped opening therein adjacent one end of said light source and the other end of said housing having a light trapped inlet therein adjacent the other end of said light source, and means for forcing a current of cooling air through said inlet opening.

HARRY H. SULLIVAN. 20
